UNITED STATES PATENT OFFICE.

LESLIE K. MORSE, OF HAVERHILL, MASSACHUSETTS.

DESIGN FOR A SHOE.

SPECIFICATION forming part of Design No. 31,769, dated October 31, 1899.

Application filed September 20, 1899. Serial No. 731,128. Term of patent 14 years.

To all whom it may concern:

Be it known that I, LESLIE KIRKWOOD MORSE, a citizen of the United States, residing at Haverhill, in the county of Essex and State of Massachusetts, have invented and produced a new and original Design for a Shoe, of which the following is a specification, reference being had to the accompanying drawing, forming part thereof.

10 In the drawing I have shown in elevation my new design for a shoe.

A is the shoe-upper. B is the opening, and C is the gore.

The characteristic feature of my design is 15 a gored shoe-upper in which the leather or other material of the shoe-upper has an opening in its upper edge extending downward and a tongue rising from the base of said opening of a height less than the depth of said 20 opening, the whole presenting the shape or configuration shown in the drawing. The gore of the shoe-upper fills said opening to a height above the height of the tongue. The opening in the shoe-upper is bounded on the 25 front edge by a convex-curved line extending downward to a point about half-way the depth of the opening, thence to the bottom of the opening in a cyma-reversa curve, the upper

part of which is convex. From the bottom 30 the curved line is continued and rising upward on a tongue forming the edge of the tongue of lines about parallel with the front edge lines of the opening. The rear edge of the opening is bounded by a line of convex curves commencing at the top and extending 35 downward and describing an arc terminating at a point below about midway the depth of the opening, and thence extending downward in a convex curve standing slightly forward, and continuing in a reverse curve rises upward on the tongue in lines about opposite the curves of the forward edge of the tongue and terminating in a point. The tongue occupies a position about parallel with the inclination of the instep.

Having now described my invention, what 45 I claim as new, and desire to secure by Letters Patent, is—

The design for a shoe, as herein shown and described.

In testimony whereof I affix my signature in presence of two witnesses.

LESLIE K. MORSE.
